UNITED STATES PATENT OFFICE

2,571,614

GLASS GRINDING AND POLISHING
MACHINE

Walter Roy Robbins, Norman, Okla., assignor of
twenty-five per cent to James L. Woods, Nor-
man, Okla.

Application September 14, 1950, Serial No. 184,856

1 Claim. (Cl. 51—135)

1

An object of the present invention is to pro-
vide an improved glass grinding and polishing
machine.

An object of the present invention is to pro-
vide a glass grinding and polishing machine em-
ploying a conventional wet grind glass belt
wherein a backing means is provided for the
belt so that the object being ground may be
pressed against the belt at the portion supported
by the backing means.

Still another object of the present invention is
to provide a novel backing means which is formed
of a pair of aluminum alloy plates with a sponge
rubber insert therebetween, providing a resilient
bearing backing means for the belt.

A further object of the present invention re-
sides in the arrangement of the pulleys whereby
the tensioning of the belt may be maintained.

A still further object of the present invention
resides in the novel bucket arrangement for the
machine whereby a grinding liquid may be
sprayed against the grinding belt for lubricating
the same, the liquid accumulating in the bucket
and being drained therefrom.

Further objects of the present invention are
to provide such means that are simple in con-
struction, economical of manufacture and of gen-
eral superiority.

Various other objects and advantages will be-
come apparent from the detailed description to
follow.

The best form in which I have contemplated
applying my invention is clearly illustrated in
the accompanying drawings, wherein:

Figure 1 is a side elevational view of the glass
grinding and polishing machine of the present
invention;

Figure 2 is a horizontal transverse sectional
view taken substantially along the plane of line
2—2 of Figure 1;

Figure 3 is a side elevational view of a portion
of the present invention showing the resilient
mounting of the lower pulley; and

Figure 4 is a front plan view of the bucket
means and resilient mounting for the lower
pulley.

Referring more particularly to the accompa-
nying drawings, wherein like numerals designate
like parts throughout, the numeral 10 designates
generally the stand for the present invention,
the numeral 12 designates generally a guide
means for the upper pulley and motor 14, the
numeral 16 designates generally the back means,
and the numeral 18 designates generally the
bucket and spray means for the belt at the lower

2

pulley, while the numeral 20 designates generally
the resilient mounting arrangement for the lower
pulley.

The stand 10 is comprised of a pair of angle
iron members 22 and 24 and a channel iron
standard 26 to which the angle iron members 22
and 24 are secured at the lower end thereof.

At the upper end of the stand 10, a motor 28
and pulley 30 are mounted. Overlying the motor
10 and pulley 28 and 30 is the guide means 12 which
includes an arcuated plate 32 and angulated end
34. The angulated end 34 is secured to the chan-
nel iron beam 26 by means of the bolts 36 and
nuts 38.

15 At an intermediate portion on the standard 26,
a bucket means 18 is secured. The bucket means
18 includes a substantially rectangular cross-
section housing 40 which has one vertical edge
thereof secured to the standard 26 by means of
20 the bolts 42. A supporting bar 44 is secured to
the channel iron standard 26 and is attached to
the bucket housing 40 by means of additional
bolts 46.

One side wall of the bucket means 18 is pro-
25 vided with an arcuated slot 48. A second pulley
50 is mounted within the bucket means 18 with
the shaft thereof extending through the arcuated
slot 48. The outer portion of the shaft 52 of the
second pulley 50 is received within the bearing
means 54. The bearing means 54 is supported by
means of a pair of brackets 56 which are pivotally
mounted on plates 58 by means of the pins 60.
The plates 58 are secured to the standard 26 by
means of the bolts 62. A hook element 64 is

35 integrally formed on the bearing housing 54 and
a second hook element 66 is fixedly secured to
the channel iron support 26. A resilient coil
spring 68 connects the two hooks 64 and 66 at
68 whereby the pulley shaft 52 will be resiliently
40 maintained in its lowermost position. The bear-
ing housing 54 may be provided with a grease
adapter 70 for supplying grease to the bearings
for the second pulley shaft 52.

The grinding belt 72 is of conventional form,
45 being the wet-grind glass belt which is employed
in many other grinding machines. The belt 72
is disposed over the upper pulley 30 and the sec-
ond pulley 50, as shown best in Figure 1. It will
readily be seen that the tautness of the belt 72
50 is controlled by the coil spring 68.

The backing means 16 includes an angulated
supporting bar 74 which has one end thereof
secured to the standard 26 by means of the
bolts 76. The angulated free end 78 of the bar
55 74 has secured thereto a pair of aluminum alloy

stop plates 80. Secured between the two aluminum alloy plates 80 is a sponge rubber insert 82. The outer aluminum plate 80 is in juxtaposition to the back of the grinding belt 72 whereby, when an object is pressed against the belt for grinding, the aluminum backing plate will provide a resilient bearing for the belt for most effective grinding.

A nozzle 84 is fixedly mounted within the front wall of the bucket housing 18 and has a liquid conduit 86 connected thereto for supplying liquid to the belt 72 for grinding purposes. A manually controlled valve 88 is positioned between the conduit 86 and the nozzle 84 for controlling the stream of fluid supplied to the belt 72. The housing 18 is also provided with a drainage outlet 90 which may be connected to a reservoir for circulating back through the conduit 86.

From the foregoing description, taken in conjunction with the drawings, it is believed that a device has been provided which will accomplish all of the objects hereinabove set forth. It will also be readily seen that the belt 72 may readily be replaced by simply raising up on the bracket plate 56 against the resiliency of the spring 68 so that the pulley 50 no longer frictionally holds the belt 72 thereon. The belt 72 may then be removed and replaced.

Certain changes may be made in the construction and arrangement of the parts of my device without departing from the real spirit and purpose, and it is my intention to cover by my claim any modified forms coming under the scope thereof.

Having described the invention, what is claimed as new is:

A glass grinding and polishing machine comprising a stand, a motor and pulley mounted on the upper end of said stand, a bucket means mounted at an intermediate portion of said stand, a resiliently mounted second pulley in said bucket means, a grinding belt disposed over said pulleys, an arcuated slot in one side wall of said bucket means for receiving an end portion of the shaft of said second pulley therethrough, said stand including a channelled member, a shaft journaled in said channelled member, a U-shaped strap pivotally mounted on said shaft, the end portion of the pulley shaft of said second pulley being rotatably journaled in the legs of said U-shaped strap, a sleeve rotatably received on said end portion of the shaft of the second pulley and between the legs of said U-shaped strap, and resilient means connected to said sleeve and a lower intermediate portion of said channelled member for tensioning said belt.
